UNITED STATES PATENT OFFICE.

HANS FOERSTERLING, OF PERTH AMBOY, NEW JERSEY, ASSIGNOR TO THE ROESSLER & HASSLACHER CHEMICAL CO., OF NEW YORK, N. Y., A CORPORATION OF NEW YORK.

METHOD OF MAKING GAS RICH IN CARBON MONOXID.

1,200,719.

Specification of Letters Patent.

Patented Oct. 10, 1916.

Application filed November 9, 1912. Serial No. 730,317.

To all whom it may concern:

Be it known that I, HANS FOERSTERLING, a subject of the German Emperor, and a resident of Perth Amboy, county of Middlesex, State of New Jersey, have invented certain new and useful Improvements in Methods of Making Gas Rich in Carbon Monoxid, of which the following is a specification.

10 This invention relates to a new and improved method for making a gas rich in carbon monoxid.

It particularly refers to a method of making such carbon monoxid gas from the carbon dioxid contained in waste gases, which otherwise would be lost, and the object of the invention is to obtain practically all of the available heat units in the original fuel as well as other products, such

20 as carbon dioxid, for further utilization toward the purpose in view thus effecting great economy in operation.

For a clearer understanding of my invention I shall describe the same in connection with the accompanying drawings forming part of this specification and illustrating in a rather diagrammatic way one form of apparatus by which my method may be carried into effect.

30 In the drawings Figure 1 is a sectional elevation of a portion of said apparatus, Fig. 2 is an elevation partly in section of the apparatus adjoining that shown in Fig. 1 and Fig. 3 is an elevation partly in section of the apparatus adjoining that shown in Fig. 2. The three figures when joined together, end to end, in the order given illustrate the complete apparatus.

Similar letters of reference indicate similar parts throughout the several views.

40 Referring to the drawings, A and A¹ indicate retorts, made of fire clay and placed in a suitable oven B connected with a gas generator C supplying gas for heating the retorts A and A¹. Bituminous coal, lignite, peat or the like fuel is charged into the retorts A and A¹ and is split up by dry distillation, due to the high heat generated by combustion of the gases coming from generator C, into tar, gas and coke. The gases,

heavily loaded with tar, escape at opening D and are cooled in a suitable condenser (not shown); thus liquefying the tar, while the incandescent residue of coke is discharged from the retorts and delivered into 55 the combustion chamber F of gas-producer G. It is essential for the success of my invention that the discharge of the coke from the retorts into the gas-producer be done quickly and be effected without exposing 60 the coke to the air, so as to avoid ignition. This manipulation may be easily carried out by means of a movable conduit H which, by any suitable means, may be arranged with its upper end beneath normally closed 65 discharge openings E, E, in the bottoms of the retorts and its lower end in air-tight connection with feed-hopper I of gas-producer G.

Gas producer G is provided in its lower 70 portion with pipe K for the admission of air or other suitable gases or a mixture of air and such other gases. The hot gases generated in producer G pass off through pipe L into a boiler M where they give off 75 their heat to the water or other liquor within the boiler. The water or other liquor under pressure enters the boiler by means of pipe M², from any suitable source (not shown), and any gas or steam generated inside of boiler M may pass off and may be controlled by means of the valves provided in pipe M³ at the top of the boiler. Pipe M³ may convey a portion of the steam or gas generated in boiler M to generator G, 80 where it may be discharged into pipe K, the remainder of said steam or gas being conducted elsewhere for useful purposes as desired. The hot producer gases entering the boiler M through pipe L travel up along 85 the tubes M¹, pass over wall M⁴, dividing the flue space into two equal parts, and down along the tubes until they leave the boiler through pipe L¹ to enter the scrubber N where they are deprived, by washing 90 with water, of any impurity detrimental to their utilization in the gas engine O which is connected with the scrubber by means of pipe L².

The energy contained in the producer gas 100

is transformed into motive power by the engine in which the gases are exploded and the gases thus, according to their constituents and their quantities respectively, producing certain other well known gases, viz. carbon dioxid and sulfur dioxid. It is evident that the gases resulting from the explosion and exhausted after the explosion are at high temperature, which fact may be taken advantage of. I prefer to conduct the exhaust gases by pipe L^3 into a boiler P , constructed similarly to boiler M , in which said gases are cooled by transferring their heat to the contents of boiler P . A pipe P^2 conducts certain liquid substances into the middle container of preheater P^1 , a pipe P^3 at the top of boiler P permitting the warm gases escaping therefrom to pass around said middle container thus preheating the liquors therein, which through pipe P^4 finally enter boiler P at the bottom. Overflow pipe P^5 maintains the contents of boiler P at a constant level. The gases escaping from boiler P through pipe P^3 and, cooled in the preheater P^1 , leave the preheater P^1 by means of pipe P^6 , connecting with pipe P^7 discharging into pipe K at the lower portion of the gas producer. The exhaust gases from the engine traveling in the other direction, cool down during their passage through boiler P and leave the same by means of pipe L^4 and enter a washing vessel Q filled with a concentrated solution of sodium carbonate, supplied from tank Q^1 . A like absorption vessel R is connected with Q by means of pipe L^5 so that the gases may travel from vessel Q to vessel R ; to the latter a fan S is connected by means of pipe L^6 so as to remove certain gases, which are of no consequence in connection with the subject matter of this invention. A cooling tower T , provided with suitable connections T^1 and T^2 for the circulation of a suitable cooling fluid, is connected to absorption vessel R by means of pipe W in order to provide a solution of potassium carbonate for filling vessel R .

I shall now describe one way of practising my invention in connection with the apparatus disclosed.

As already mentioned above, bituminous coal, lignite, peat or the like fuel is charged into the gas retorts A and A^1 and submitted there to dry distillation whereby coke and some by-products such as gas, tar, etc., are produced. What is done with the by-products of the distillation, after they have escaped through D to a condensing apparatus, etc., is of no consequence in connection with the subject matter of my invention, as they may find various uses. The incandescent coke left as residue in the retorts is charged into the combustion chamber of producer G to be there treated in a special way with the

purpose in view which will be more fully explained below. 65

If regular producer gases are utilized in a gas engine for the generation of power, the gas is mixed with air in order to create an explosive mixture and the more nearly 70 this explosion conforms to theoretical combustion the more nearly do the exhaust gases consist of an ideal composition of nitrogen and carbon dioxid gas, with only such admixtures as are due to impurities in the fuel, 75 for instance a small content of sulfur dioxid due to the sulfur in the original combustible.

The subject matter of my invention is chiefly centered in the carbon dioxid of the 80 exhaust gases with reference to its utilization in connection with the considerable heat stored in the incandescent coke with a desire to produce a gas rich in carbon monoxid at the lowest cost. It is evident therefore that the carbon dioxid of the exhaust 85 gases should be brought into a suitable and proper form so as to cause a reduction of said carbon dioxid into carbon monoxid by means of the highly incandescent coke. 90

If it be assumed that the gas producer G is already running as described, to give the supply of fuel gas to the gas engine, the exhaust gases from the engine would of course continuously have a certain composition consisting chiefly of nitrogen and carbon dioxid. In order to obtain these latter gases in the most beneficial form and without wasting the heat carried by the same, the exhaust 95 gases are conducted from the gas engine 100 into boiler P where they give off heat; the cooled gases pass then into the washing vessel Q containing a solution of sodium carbonate, where the sulfur dioxid is removed by the simultaneous generation of carbon dioxid. The remaining exhaust gases containing the carbon dioxid from washing vessel Q then pass into absorption vessel R which contains potassium carbonate solution and which eagerly absorbs all the carbon 110 dioxid gas, whereupon the remaining nitrogen gas and the excess of oxygen is removed by fan S . The potassium carbonate solution as it comes from cooling tower T , (which is connected with boiler P by means of overflow pipe P^5), has a temperature sufficiently 115 low to allow complete absorption of the carbon dioxid. After such absorption the saturated solution is conducted by pipe P^2 from vessel R to preheater P^1 and thence into the 120 boiler P by pipe P^4 to be heated in the boiler by the hot exhaust gases, whereby the carbon dioxid is driven out of the potassium carbonate solution and passes through pipe P^3 around preheater P^1 to pipes P^6 , P^7 which 125 discharge into pipe K at the lower portion of the gas producer G , the carbon dioxid passing thence into the coke bed of the pro-

ducer to be reduced there into carbon mon-
5 oxid gas by the highly incandescent coke. The generated gases obviously leave the gas producer at a very high temperature which is taken advantage of in boiler M to which they pass through pipe L. As I have already shown in U. S. Letters Patents Nos. 1,015,549, and 1,015,550, granted to me January 23, 1912, I am able to produce steam 10 of high pressure in boiler M, and to produce such steam in such great quantities that a part of it is fully sufficient to supply the gas generator if, in case of emergency, it should be run in the well known method of 15 blowing in a mixture of air and steam; for this purpose pipe M³ connects with pipe P⁷ discharging into pipe K at the lower portion of the producer, the operation of said pipes being controlled by suitable valves as 20 shown.

It is evident that the considerable amount 25 of heat carried into the gas producer with the charge of highly incandescent coke goes a long way to cause the reduction according to the equation $C + CO_2 = 2CO$. As this reaction, however, requires a great amount of heat, I blow a limited supply of air into producer G through pipe X. The gas thus produced is very rich in pure carbon mon- 30 oxid inasmuch as the exhaust gases from the engine O were carefully freed from impurities and the absorption of carbon dioxid in and subsequent liberation from the potassium solution results in a pure carbon diox- 35 id. If this rich gas, the production of which I have now described, is exploded in the gas engine O, I arrive again at the production of exactly the same kind of exhaust gases to which I have hereinabove referred 40 in describing the operation of my invention.

It is obvious that my invention is not limited to the exact apparatus shown or described, but that I am entitled to any fair, equivalent thereof whereby my method may 45 be carried out, it being requisite only that practically pure carbon dioxid coming from whatever sources, as for instance combustion, limekilns, fermentation processes, etc., be reduced by highly incandescent coke, that 50 said incandescent coke be transferred in this state from a suitable apparatus, such as an apparatus for dry distillation, into the producer and that the reduction of a regulated amount of carbon dioxid gas be effected by 55 the heat stored in the incandescent coke, and by the residual heat left by the gas making process.

It is immaterial in which way some details, which however are very important to 60 economical success, are carried out; for instance it is immaterial whether gas retorts are used for the generation of coke or whether this is done in regular coking ovens, inasmuch as these factors are largely de-

cided by the size of the gas producer plant. 65 It is immaterial whether the gas retorts are erected above the gas producer inasmuch as the gas retorts may be erected in a suitable oven beside the gas producer; in this case the incandescent coke for example may be 70 discharged into a basket having an air-tight cover and thus charged into the gas producer or be distributed in suitable portions over the gas-producer; it is also immaterial at which periods I add incandescent coke 75 to the gas producer to replenish the gasified coke.

It is furthermore immaterial as to what kind of a gas producer I gasify the coke in as any such apparatus for the production 80 of gas for technical and domestic use from fuel by gasifying the same will answer my purpose; in what kind of washers and absorbers the removal of the impure gases and the final absorption of the carbon dioxid 85 respectively takes place, the most material point being the utilization of the waste heat for the liberation of the carbon dioxid gas from the absorbing liquid.

It is obvious therefore that I do not re- 90 strict myself to the arrangement or kind of apparatus shown or to the steps of the process described in connection therewith, fur- ther than the scope of the appended claims demand.

What I claim and desire to secure by Let- 95 ters Patent is:

1. The cyclic process of making and burn- 100 ing gas having a high and substantially constant content of carbon-monoxid consisting in providing a body of incandescent coke, conducting carbon-dioxid, steam and air therethrough whereby a gas rich in carbon-monoxid is produced, cooling the off-going producer gas containing carbon-monoxid 105 and forming steam thereby, burning the cooled producer gas containing carbon-monoxid, cooling the products of said com- bustion, separating the carbon-dioxid from the other products of said combustion and 110 - injecting a portion of the steam derived from the cooling of the producer gas with an admixture of air and said carbon-dioxid into the body of incandescent coke.

2. The cyclic process of making and burn- 115 ing gas having a high and substantially constant content of carbon-monoxid consist- ing in intermittently providing a body of incandescent coke, conducting carbon-dioxid, steam and air therethrough whereby a gas 120 rich in carbon-monoxid is produced, cooling the off-going producer gas and forming steam thereby, burning the producer gas, separating the carbon-dioxid from the other products of said combustion by absorbing 125 the carbon-dioxid in a suitable liquid absorbent, driving the carbon-dioxid from the absorbent by the heat of the heated products

of combustion of the producer gas, returning the carbon-dioxide-free absorbent to absorb other carbon-dioxide and injecting a portion of the steam derived from the cooling of the producer gas with an admixture of air and said freed carbon-dioxide into the body of incandescent coke.

In testimony whereof I have signed this specification in the presence of two subscribing witnesses.

HANS FOERSTERLING.
